CLAIM

The ornamental design for an ashtray, as shown and described.

DESCRIPTION

FIG. 1 is a top plan view of an ashtray showing our new design;

FIG. 2 is a bottom plan view thereof;

FIG. 3 is a left side elevational view thereof;

FIG. 4 is a right side elevational view thereof;

FIG. 5 is a rear elevational view thereof;

FIG. 6 is a front elevational view thereof; and,

FIG. 7 is an isometric view thereof.

The broken line showing of "Team Logo" is for illustrative purposes only and forms no part of the claimed design.
